UNITED STATES PATENT OFFICE.

KONSTANTYN BABECKI, OF WINFIELD, NEW YORK.

DESIGN FOR AN ALTAR-CLOCK.

51,090.

Specification for Design.

Patented July 31, 1917.

Application filed June 5, 1917. Serial No. 173,053. Term of patent 7 years.

To all whom it may concern:

Be it known that I, KONSTANTYN BABECKI, a subject of the Emperor of Austria, and a resident of Winfield, in the county of Herkimer and State of New York, have invented a new, original, and ornamental Design for an Altar-Clock, of which the following is a specification, reference being had to the accompanying drawing, forming part thereof.

The figure is a front elevational view of an altar clock, showing my new design.

I claim:—

The ornamental design for an altar clock as shown.

KONSTANTYN BABECKI.
